UNITED STATES PATENT OFFICE.

ARTHUR TAYLOR, OF CENTRALIA, ILLINOIS.

RAILROAD-SKATE.

1,157,264.

Specification of Letters Patent.

Patented Oct. 19, 1915.

Application filed July 13, 1915. Serial No. 39,622.

To all whom it may concern:

Be it known that I, ARTHUR TAYLOR, a citizen of the United States, and a resident of Centralia, in the county of Marion and State of Illinois, have invented a new and useful Improvement in Railroad-Skates, of which the following is a specification.

My invention is an improvement in railroad skates, and the invention has for its object to provide mechanism in connection with the tracks of a gravity or hump switch, for permitting the operator in the tower to place the skates on any branch or track of the yard, thus dispensing with the services of the usual operative, and insuring that the skates will be placed on the proper track, and in time to stop the car or cut of cars in ample time.

In the drawings:—Figure 1 is a top plan view showing the skates in place, Fig. 2 is a section on the line 2—2 of Fig. 1, looking in the direction of the arrows adjacent to the line, and Fig. 3 is a section on the line 3—3 of Fig. 2, looking in the direction of the arrows adjacent to the line.

As is known, the operation of switching is greatly facilitated by the hump or gravity arrangement of yards, wherein the cars are distributed from the hump and roll down by gravity to the several tracks. A tower-man on the hump operates the switches to deflect the cars to their respective tracks, and as a rule a switchman rides each car or cut of cars down. That is, the operator will have charge of all of the cars that are intended for a single track, and since the cars sometimes attain a considerable speed should there be a failure of the hand brakes, damage is liable to result. To prevent such damage an operative is stationed somewhere in the yard with the so-called skates, which he will place upon the rails in front of a car that is out of control.

The present invention has for its object to provide mechanism capable of being operated by the tower-man for placing these skates.

The present embodiment of the invention is shown in connection with the rails 1 of a siding track, the rails being supported by the usual ties 2, and the operating mechanism is arranged in a pit beneath the track and extending transversely of the rails, and comprising side plates 3, of a length to ex-

tend beyond the rails at each side, these plates being placed between the ties and beneath the rails.

The plates are of sufficient width to house the operating mechanism, and the said mechanism comprises a central shaft 4, which is journaled in bearing plates 5, secured to the inner faces of the plates 3, and at a point half-way between the rails. This shaft has a cross head 6, secured thereto near one end, and journal pins 7 and 8 are journaled in bearings in the ends of the arms.

Links 9 and 10 are connected with the respective journal pins 7 and 8, each link having a bearing 11 for engaging the pins, and the cross head has a central hub 12, which fits upon the shaft 4, and is secured thereto by a cross pin 13. The links 9 and 10 extend in opposite directions, and the journal pins 7 and 8 are of such length that loops in the ends of flexible members 14 and 15 may engage over the heads of the journal pins on the opposite side of the cross head from the bearings 11 of the links.

The skates 16 are of ordinary construction, adapted to be set upon the track and having at the end remote from the hump an upward extension 17 for engagement by the wheels of the cars to check the movement thereof. Each skate is provided on its outer side with a rod or cylindrical arm 18, the arms or rods extending parallel with the long axes of the skates, and each arm or rod is integral with the skate at the end adjacent to the hump 17, as indicated at 19. Each skate is also provided on its inner side with depending flanges 20, which engage on the inner side of the head of the rail to lock the skate to the rail.

A shaft 21 is journaled between the plates 3 at the outer side of each rail, and near the lower edges of the plates, and a pair of arms 22 is rigidly connected with each shaft. Each arm has hubs 23, which fit over the shaft, and are secured thereto by cross pins or screws 24, and the arms of each shaft extend upwardly toward the adjacent arm or rod 18.

Each arm is provided with a bearing 25 at its upper end and the bearings of each pair of arms engage the adjacent rod or arm 18. Thus the skates are mounted to swing on the arms, and the shaft 21 is so arranged that when the skates are in place

on the rails and the arms are moved outwardly to move the skates from off the rails, the skates will first be lifted slightly but far enough to disengage the flanges 20 from the 5 rails. That is, at the first movement of the arms the skates are lifted, and they are then swung outwardly and away from the rails as indicated in dotted lines in Fig. 2.

A link 26 is arranged at or outside of each 10 rail, each link having a bearing at one end which engages the adjacent arm or rod 18, and the outer end of each link is pivoted to the outer end of a slide bar 27, which is mounted to slide in bearing clips 28, secured 15 to the upper face of a transverse partition or shelf 29, extending between the plates 3, intermediate their upper and lower edges. These plates 29 extend from beneath the rail to the outer ends of the plates 3 and at their 20 inner ends the plates are notched or recessed at the respective plates 3 as indicated at 30 to permit the passage of the arms 22. The links 9 and 10 extend in opposite directions, and the outer end of each link is received between 25 the arms 31 of a fork on the inner end of the adjacent slide bar, and the links are pivoted to the arms as shown.

It will be evident that when the shaft 4 is oscillated by means of the flexible members 14 and 15 from the full line position of 30 Fig. 2 to the dotted line position, the slide bars 27 will be moved outwardly away from the rails, and because of the link 26 the arms 22 will be swung to first lift the skates from 35 the rails and to afterward swing them away from the rails. These flexible members 14 and 15 extend to the tower or to any other suitable place and are connected with an operating lever in the usual manner.

40 Signal mechanism is arranged adjacent to the skates, the said mechanism comprising a post 32 rigidly secured to the outer face of one of the plates 3, and the post carries a signal lamp 33, having its opening toward 45 the direction from which the cars come toward the skates. A plate or disk 34 is provided for covering the opening 33, and the said plate is mounted on one end of a lever 35, which is pivoted to a bracket arm 36, 50 extending laterally from the post. The lower end of the lever is connected by a link 37 with the adjacent link 26, and it will be evident that when this link is moved outwardly to move the skate away from the rails, the lever will be operated to move the disk 34 from in front of the signal lamp 33.

60 The operation of the improvement is as follows:—When the tower-man sees that a car or cut of cars cannot be checked by the switchman in charge or for any other reason he will operate the lever, not shown, connected to the skates of the particular track upon which the car or cut of cars is moving in a direction to move the skates on to the 65 track. Thus if the parts were in the dotted

line position of Fig. 2, he will swing the lever in a direction to make tension on the flexible member 14. This will swing the cross head 6 into the full line position of Fig. 2. The slides 27 will move inward toward each other, and the arms 22 will be swung to simultaneously move the skates toward each other and to position them on the treads of the rails. At the same time the signal lamp 33 which is normally uncovered by the disk 34 will be covered cutting off the light and showing the tower-man that the skates are properly placed.

70 It will be noted from an inspection of Fig. 3 that that end of each skate adjacent to the moving cars, that is, adjacent to the tower-man is beveled and the car wheels will run upon the bevel end on to the body of the skates and will strike the hump or extension 75 17. The skates will be moved longitudinally, slipping the rods 18 out of the bearings 25 of the arms, and out of the bearings of the links 26, and the friction will finally check the momentum of the cars, stopping them in time to prevent damage.

80 After the cars have been stopped the skates may be removed from beneath the wheels and returned to proper position with respect to their placing mechanism. The signal lamp 33 is at all times visible to the 85 tower-man, showing that the skates are off the track until the moment when they are placed on the track, and by watching the signal, the tower-man may know that his 90 skates have been properly placed. The 95 tower-man since he operates the switches to deflect the cars knows the precise track upon which the car or cut of cars that may be out of control are going, and he can easily place the skates in ample time to stop them.

100 I claim:—

110 1. In combination with the rails, and the holding skates for the rails, of a pit arranged transversely of the track beneath the rails, a shaft journaled transversely of the pit at each rail and on the outer side thereof, a pair of parallel arms extending upward from each shaft, and having a connection with the adjacent skate to lift the skate from the rail and swing it outwardly away from the rail when the shaft is oscillated in the proper direction, operating means for simultaneously swinging the skates in opposite directions arranged transversely of the pit between the rails, said mechanism comprising a shaft having a cross head, means connected with the ends of the cross head for oscillating the shaft, a slide bar in the pit at the outer side of each rail and having guided movement transversely of the rail, a link connecting each slide bar to one end of the cross head, and a connection between the outer end of each link and the adjacent 115 120 125 130 skate.

2. In combination with the rails, and the

- holding skates for the rails, of a pit arranged transversely of the track beneath the rails, a shaft journaled transversely of the pit at each rail and on the outer side thereof, 5 a pair of parallel arms extending upward from each shaft, and having a connection with the adjacent skate to lift the skate from the rail and swing it outwardly away from the rails when the shaft is oscillated in the proper direction, operating means for simultaneously swinging the skates in opposite directions arranged transversely of the pit between the rails, said mechanism comprising a shaft having a cross head, means connected 10 with the ends of the cross head for oscillating the shaft, slide bars having guided movement transversely of the rails and connected to the ends of the cross heads at their inner ends and to the skates at their outer 15 ends to swing the skates on to and away from the rails when the slide bars are moved in opposite directions.
3. In combination with the rails, and the holding skates for the rails, of a pit arranged transversely of the track beneath the rails, a shaft journaled transversely of the pit at each rail and on the outer side thereof, a pair of parallel arms extending upwardly from each shaft, and having a connection 20 with the adjacent skate to lift the skate from the rail and swing it outwardly away from the rail when the shaft is oscillated in the proper direction, operating means for simultaneously swinging the skates in opposite directions arranged transversely of the pit between the rails, said mechanism comprising a shaft having a cross head, means connected 25 with the ends of the cross head for oscillating the shaft, and a connection between the ends of the cross head and the skates for simultaneously swinging the skates in opposite directions when the shaft is oscillated.
4. The combination with the rails and the skates adapted to be seated upon the rails for checking the movement of a car, each 30 skate having at the outer side thereof an arm rigidly connected therewith and having that end toward which the cars are moving free from the skate, operating mechanism for simultaneously moving the skates in opposite directions, shafts journaled at the outer sides of the skates and connected with the operating mechanism for oscillating the shafts when the said mechanism is operated, 35 and a pair of arms on each shaft and provided with bearings for engaging the adjacent arm of the skate.
5. In combination with the rails, of a pair of holding skates for the rails, a pair of arms for each skate, a shaft journaled at the outer side of each skate, the adjacent arms being rigid with the shaft, each pair of arms having registering bearings at their upper ends and each skate having a rigid 40 arm extending longitudinally thereof and connected to the skates at the end remote from the approaching cars, said arms being adapted to engage the bearings, and means for simultaneously oscillating the arms in opposite directions.
6. In combination with the rails, of holding skates adapted to be seated on the rails, each skate having an arm extending longitudinally thereof and connected to the skate at the end remote from the approaching cars, a pair of swinging arms pivoted below and at the outer side of each rail, the members of each pair having bearings for engagement by the arms of the adjacent skate, and means for simultaneously swinging the 45 arms in opposite directions.
7. A skate for seating on the rail of a railroad track, each skate having that end adjacent to the approaching cars beveled and having at the other end a hump or upward extension, each skate having at the outer side thereof an arm extending longitudinally of the skate and connected to the skate at the end adjacent to the hump or extension, means engaging the arm of the 50 skate for placing the skate on the rail and operable from a distance and releasable from the arm, said means comprising a shaft journaled longitudinally of the skate at the outer side of the rail, the shaft having a pair of rigid arms extending in parallel relation therefrom, the arms having registering bearings for receiving the arm of the skate.
8. The combination with the rails, of the holding skates for the rails, each skate having an arm extending longitudinally at the outer side thereof and connected to the skate at the elevated end thereof, a pair of arms for each skate, each arm having a bearing 55 for slidably engaging the arm of the skate, and the arms of each pair being mounted to swing on a common axis, and means for simultaneously swinging the pairs of arms in opposite directions to seat or unseat the skates, said means comprising a shaft having a cross head and journaled between the rails, a slide mounted to move transversely of each rail beneath the same and connected to one end of the cross head at its inner end, a link connecting the outer end of each slide to the arm of the adjacent skate and having a 60 slidable connection with the skate, and means for oscillating the shaft in opposite directions.
9. The combination with the rails, of the holding skates for the rails, each skate having an arm extending longitudinally at the outer side thereof and connected to the skate at the elevated end thereof, a pair of arms for each skate, each arm having a bearing for slidably engaging the arm of the skate, and the arms of each pair being mounted to swing on a common axis, and means for simultaneously swinging the pairs of arms 65

in opposite directions to seat or unseat the skates.

10. A skate for seating on the rail of a railroad track, each skate having that end adjacent to the approaching cars beveled and having at the other end a hump or upward extension, each skate having at the outer side thereof an arm extending longitudinally of the skate and connected to the 10 skate at the end adjacent to the hump or extension, means slidably engaging the arm of the skate for placing the skate on the rail and operable from a distance and releasable from the arm.
11. A skate for seating on the rail on a railroad track, each skate having that end adjacent to the approaching cars beveled and having at the other end a hump or upward extension, each skate having at the 15 outer side thereof an arm extending longitudinally of the skate and connected to the 20

skate at the end adjacent to the hump or extension.

12. The combination with the rails, of a holding skate, means connected with the 25 skate for moving the skate onto and off of the rail, said means being operable from a distance, and said connection being releasable from the skate when the skate is pushed longitudinally of the rail in one direction. 30

13. The combination with the rails and the holding skates for the rails, of means detachably connected with each skate for swinging the skate onto and off of the adjacent rail, a common operating means for 35 the swinging means of the skates and operable from a distance, a signal, and a connection between the signal and the moving means for the skates for controlling the signal.

ARTHUR TAYLOR.
